UNITED STATES PATENT OFFICE.

ARTHUR A. GRONROS, OF PONTIAC, MICHIGAN.

SELF-LOCKING SHORE.

Application filed November 12, 1920. Serial No. 423,529.

To all whom it may concern:

Be it known that I, ARTHUR A. GRONROS, a citizen of the United States, residing at Pontiac, in the county of Oakland and State 5 of Michigan, have invented certain new and useful Improvements in a Self-Locking Shore, of which the following is a specification.

This invention relates to a class of devices 10 which are generally employed in shoring or "propping up" operation and including shores or propping means capable of use as temporary supports under the floors, beams, etc. when building concrete or other 15 structure.

An object of the invention is to provide a shore or prop device of the character above specified which is both adjustable and self-locking.

20 An additional object is to provide a device of the character specified having its various parts so co-related as to provide a structure strengthened and reinforced to withstand the strains and pressures to which 25 it may be subjected, and, at the same time, be of a comparatively light and durable structure.

With the above and other objects in view, the invention may be considered as residing 30 generally in the details of construction, combination and arrangement of parts as will be hereafter pointed out and explained, reference being had to the accompanying drawings, wherein:

35 Figure 1 is a front elevation of the shoring device constructed in accordance with the principles of the invention,

Figure 2, is a horizontal sectional view taken on the line 2—2 of Figure 1.

40 Figure 3, is a similar section taken on the line 3—3 of Figure 1;

Figure 4, is a detailed, fragmentary, view illustrating the self-locking feature of the invention,

45 Figure 5 is a detailed sectional view showing the manner in which the locking elements are pivotally supported.

The invention consists broadly in longitudinal adjustable prop members formed 50 respectively of a frame and a supporting column therefor.

The supporting column 1 may be of hollow pipe construction and is supported adjacent one end by a bearing block or plate 55 2. To the other end of the column is secured a keeper 3 consisting of a horizontally

disposed plate having notches 4 formed in opposite edges to provide guideways into which fit portions of the adjustable frame. The keeper may be of any desirable design 60 and is intended to guide the prop members of the device in their adjustment and to hold them relatively spaced.

The same consists of a pair of laterally spaced strip of hangers 6, secured at one end 65 by a cross bar or head block 7 upon which the load is adapted to rest. Connecting the hangers of the frame at a point below the road supporting block are braces 8, extending crosswise of the frame on opposite sides 70 and bent outwardly to provide for the passage of the keeper therebetween and its movement up and down within the frame.

The hangers of the frame are preferably extended to a sufficient distance below the 75 braces to permit of a slight amount of spring in order that the lowermost extremities of the hangers may be forced inwardly toward each other for the purpose of releasing the grip means. The grip means consists in 80 a looped element pivotally secured to the lower end of each hanger with its head or looped end 10 embracing the column 1 and having a snug fit therewith as indicated to advantage in Figure 3 of the drawings. 85 The free ends of the loops are fastened to the hanger on opposite sides; the end of the hanger being cutaway as at 11 to receive the free end. The upper edge of each cutaway portion is beveled to permit of a 90 certain upward movement of the element. It is to be noted that the head 10' of one of the grips is smaller than and fits into the head of the other grip so as to embrace the column from the opposite side. It is 95 thus obvious that the column is entirely enclosed between the head 10 and 10' of the gripping element.

Connecting the ends of the hanger is a band or loop 12 which embraces the hangers 100 on opposite sides and in spaced relation thereto. This hanger is supported upon bolts or other fastening means 13 which extend crosswise to the hangers 6 and provide the pivot for the loop elements. Securing 105 nuts 14 on the ends of the bolts hold the loop 12 in place. To the bolt of one hanger the free ends of the loop are fixedly secured while the bolt of the adjacent hanger is accommodated in a slot 15 which permits 110 a limited amount of movement between the loop and that particular hanger. The grip

releasing means includes a screw 16 threaded to one end of the loop and provided with a head 17 adapted to bear against a plate 18 fastened to the edge of the adjacent hanger. At the outer end of the screw a handle 19 is provided for turning the screw and advancing it either inwardly or outwardly of the loop, thus releasing or permitting the grip to actuate as the case 10 may be.

In the assembling of the members, the frame is mounted upon the column with the latter extending upwardly between the hangers 6 and held in spaced relation thereto by 15 means of the keeper which bridges the space between the hangers as is shown to advantage in Figure 1. The hangers fit into the notches of the keeper and thus serve as guiding posts for the latter. When the grip is 20 disposed about the column the lower portions of the hangers are flexed inwardly and on account of their tendency to spring back to their original position, they constantly exert a pull upon the grips which causes 25 them to embrace the column more firmly therebetween, thus locking the same to the post and rendering the members relatively immovable. At the same time it is to be noted that the angular disposition of the 30 gripping element with respect to the hangers is such that the force exerted upon the grip by the downward tendency of the frame under the pressure of a load, is such as to likewise cause the grip to obtain a firmer hold 35 upon the column. In other words, the grip automatically actuates to lock the frame against motion toward the lower end 2 of the post although permitting it to move freely in the opposite direction. Motion in the opposite direction would serve to release the 40 grip.

To render the lock grip inoperative for the purpose of facilitating adjustment of

the members longitudinally of one another the handle 19 may be manually operated to 45 force the screw inwardly against the plate 18 of the hanger arm so that the latter will be swung inwardly under continual pressure of the rotated screw, which inward motion of the hanger serves to release the head 10 from 50 its grip on the column.

Since the grip automatically operates to clutch the column the same will be automatically locked in any adjusted position on the frame and firmly held until released by the 55 manually operated release mechanism. While illustrated as being designed to provide an under support for floor beams, etc. it is obvious that the invention may likewise be employed as an adjustable prop or brace capable of use for facing timbers and other purposes.

Having thus described my invention what I claim as new is:—

In an adjustable shore including a column, a base secured to the lower end of the column, a top member slidably associated with the column toward and away from the base including a head block and depending hangers, and a grip means associated with the lower ends of the hangers for engaging the column, means for releasing the grip members including a U-shaped band having parallel legs pivotally connected to one hanger and a curved connecting portion embracing the other hanger, a slot and pin connection between said legs and the last mentioned hanger, and an adjustable member carried by the curved connecting portion for 60 engaging the last mentioned hanger.

In testimony whereof I affix my signature in presence of two witnesses.

ARTHUR A. GRONROS.
